EXERCISE BELT

Achill W. Brand, Morro Bay, Calif.

Application April 1, 1930. Serial No. 440,769

3 Claims. (Cl. 174—175)

My invention relates to improvements in exercise belts, and particularly to a structure of this character intended and adapted to be used in exercising, massaging and stimulating the muscles 5 and nerves in regions adjacent the spine and especially in the cervical regions.

An object of my invention is to provide an exercise belt which is adaptable for use by the individual to accomplish exercising, massage and 10 stimulation of the muscles and nerves at vital centers, to thus relieve congestion, without the aid of a specially trained assistant or other manipulator.

A further object is to so construct the parts 15 that they can be adjusted for use by individuals of different sizes and to suit various conditions in the individual.

Still another object is to provide for the utilization 20 to aid in the stimulation and remedial treatment.

With the above and other objects in view, which will be apparent to those skilled in the art, my invention includes certain novel features of construction and combinations of parts which will 25 be hereinafter set forth in connection with the drawing.

In the drawing:

Figure 1 is a view in perspective showing one manner of using my improved exercise belt.

30 Fig. 2 is a fragmentary view illustrating another use.

Fig. 3 is a view in section showing the electric padded slipper.

Fig. 4 is a view in plan of the showing in 35 Fig. 3.

Fig. 5 is a detail view to better show the neck-pad.

Fig. 6 is a fragmentary view showing another form of slipper.

40 My improved exercise belt is intended primarily to be used by an individual by being caught around the neck, head, or upper shoulder portions at one extremity and beneath the sole of the feet, to somewhat bow the body, and the individual then 45 sitting or reclining can accomplish the desired massage movement and stimulation by movement of one leg at the time with all other portions of the body.

The belt member 1 which is of webbing or yielding 50 material has a buckle or other fastening 2 at one end to receive the remaining end 3 so that the length of the belt can be adjusted to suit the requirements of each individual user.

Slipper portions 4 are fitted upon the belt member 55 1 so that the belt will bear against the in-

step portion, and these slippers are preferably adjustable to suit the requirements of the individual, the slippers being preferably carried by plates 5 which give greater rigidity.

Upon the remaining end of the belt 1 a neck-pad 6 is fitted, this pad being either secured in place or slidable upon the belt to be adjusted to individual requirements.

With the structure made up in the manner set forth the individual user can adjust the length 65 of the belt 1 to suit his own requirements, and the belt is fitted for use with the feet encased in the slipper portions 4 and the neck-pad 6 caught around the cervical portion at an elevation best suited to treatment of the particular individual. As shown in Fig. 1, the neck-pad portion 6 is located adjacent the lower end of the neck, and in Fig. 2 it is illustrated as in contact with the back of the head, and, it will be appreciated that this portion of the belt can 75 be fitted to bear and draw upon any desired portion of the cervical and adjacent areas. The belt 1 is preferably adjusted so that the body of the user will be bent at the waist and the user can then sit or recline upon the floor or any 80 other surface and by rocking motion and manipulation of the legs the desired massage and stimulating force can be exerted. I have found that very beneficial results are attained when the user sits and rocks upon a small relatively hard 85 cushion, as illustrated at 7 in Figure 1, as the torso can be rocked and twisted to better advantage when supported in this way; however, my improved exercise belt can be used in various manners to suit the requirements of each 90 individual.

In some instances it may be found desirable to give electrical applications to heat or otherwise stimulate the vital centers upon which the belt is fitted and the electric circuit wires 8 can 95 be led to connect with suitable coils 9 within the soles of the slipper portions 4, while circuit wires 10 are led to connect with coil wires 11 in the neck-pad 6. If desired, these circuit wires can all be connected to be controlled from a switch 12 carried by one end of the belt 2 or at any other suitable and convenient location. The circuits might be jointly or separately controlled and the coils can be constructed to give a low, 105 high or variable heat and to accomplish the desired stimulation of the vital centers.

As illustrated in Fig. 6 the slipper portions 13 might be mounted in conjunction with widened portions 14 permanently formed or located on 110

the belt 15, and the structure can be varied in other ways.

While I have herein shown and described only certain specific embodiments of this invention 5 and have suggested only certain possible modifications, it will be appreciated that a number of changes and variations can be resorted to without departing from the spirit and scope of my invention.

10 I claim:

1. An exercise belt comprising, an elongated belt member of non-elastic webbing material, and adjustable fastening means to connect the ends of said elongated member to form a long 15 loop, the length of the loop and the width of the webbing material being such that one side of the looped belt member can be caught around the neck and cervical portion and the opposite side can be engaged by the feet whereby movement of the feet with alternate treading motion 20 will move the neck engaging portion back and forth across the cervical region to produce a vibratory massaging action without chafing.

2. An exercise belt comprising, an elongated 25 belt member of non-elastic webbing material, adjustable fastening means to connect the ends of said elongated member to form a long loop, the length of the loop and the width of the webbing material being such that one side of the 30 looped belt member can be caught around the neck and cervical portion and the opposite side can be engaged by the feet whereby movement of the feet with alternate treading motion will move the neck engaging portion back and forth 35

across the cervical region to produce a vibratory massaging action without chafing, a pad portion mounted and held in the upper loop of the belt member to be moved back and forth across the cervical region to produce heating friction as the belt member is manipulated, and slipper portions adjustably held on the belt member in the opposite loop to receive the feet. 80

3. An exercise belt comprising, an elongated belt member of non-elastic webbing material, 85 adjustable fastening means to connect the ends of said elongated member to form a long loop, the length of the loop and the width of the webbing material being such that one side of the looped belt member can be caught around the neck and cervical portion and the opposite side can be engaged by the feet whereby movement of the feet with alternate treading motion will move the neck engaging portion back and forth across the cervical region to produce a vibratory massaging action without chafing, a pad portion mounted and held in the upper loop 90 of the belt member to be moved back and forth across the cervical region to produce heating friction as the belt member is manipulated, slipper portions adjustably held on the belt member in the opposite loop to receive the feet, and an electrically heated coil in said pad to increase the heat application beyond the possibility of frictional heating to thus increase the stimulating effect as the belt member is manipulated to apply vibratory massage forces over the cervical region. 95
